CLAIM

The ornamental design for a geometric shaped hexagon container with a storage compartment in the cover, as shown and described.

DESCRIPTION

FIG. 1 is an exploded view of a geometric shaped hexagon container with a storage compartment in the cover in an open configuration showing our new design;

FIG. 2 is a perspective view of a geometric shaped hexagon container with a storage compartment in the cover in an open configuration;

FIG. 3 is another exploded left side view of a geometric shaped hexagon container with a storage compartment in the cover in an open configuration, the exploded right side view being a mirror image thereof;

FIG. 4 is a top plan view of a geometric shaped hexagon container with a storage compartment in the cover in a closed configuration; and,

FIG. 5 is a bottom plan view of a geometric shaped hexagon container with a storage compartment in the cover.
